UNITED STATES PATENT OFFICE

HENRY F. GOYETTE, OF BOSTON, MASSACHUSETTS, ASSIGNOR TO UNITED SHOE MANUFACTURING CORPORATION, OF PATERSON, NEW JERSEY, A CORPORATION OF NEW JERSEY

MACHINE FOR AND METHOD OF OPERATING UPON SHOES

Application filed August 16, 1929. Serial No. 386,285.

This invention relates to machines for and methods of operating upon shoes, and is herein shown and described as embodied in a machine for treating a portion of the upper of a lasted shoe to prepare the shoe for the reception of a sole.

According to one method of shoe manufacture the sole is secured to the upper of the lasted shoe by cement, and it is an object of the present invention to provide an improved machine for preparing the portion of the upper to which the sole is to be attached in such a manner that the cement will adhere strongly to it and, consequently, a secure and permanent attachment of the sole will be obtained. The treatment for which the illustrated machine is designed consists in removing the surface finish from the overlasted portion of the upper and roughening, by abrasion, scratching or cutting, the said overlasted portion to produce a suitable cement receiving surface thereon.

This operation has heretofore been performed by a tool mounted upon a rotating shaft, the lasted shoe being held in the hands of the operator and being presented manually to the tool. The extent and location of the area tooled and the depth of the tooling has been determined entirely by the operator's judgment, and a high degree of skill and care was required to produce good, uniform work.

An important feature of the present invention consists in the provision, in a machine for performing the above described upper tooling operation, of mechanical means for feeding the work past the tool, preferably at a substantially uniform rate, thereby greatly facilitating the production of uniformly satisfactory results and reducing the amount of skill and care demanded of the operator.

In the illustrated machine, which is adapted to operate upon a shoe lasted, for example, by the method described in the prior application of George Goddu Serial No. 386,097, filed Aug. 15, 1929, there is provided feed mechanism which operates upon the work by engagement with the insole of the lasted shoe. As shown, the machine operates upon the lasted shoe prior to the trimming operation by which the insole lip or rib and the

upstanding margin of the upper is removed, the feed mechanism being arranged to engage the lip of the insole. The feed mechanism may comprise oscillating fingers engaging the inner side of the insole lip and causing the work to move continuously in the direction in which said lip extends while the upper treating tool is operating upon the portion of the upper overlying and parallel to the insole outside of the lip.

Another feature of the invention resides in the provision of work guiding means cooperating with the insole lip or rib and engaging the upstanding portion of the upper in the angle formed by the overlasted portion of the upper and the upstanding margin of the same, which lies against the outer side of the insole lip or rib. In the illustrated embodiment of the invention the work guiding means comprises a frusto conical member adapted to enter the angle above referred to and not only guide the work but also constitute an abutment to resist the thrust of the work feeding fingers as they penetrate the insole lip to secure operative engagement therewith.

In this connection invention is also to be recognized in a frusto conical roughening tool, in combination with a work guide, operating in the angle formed by the insole lip or rib and the shoe bottom, permitting the roughening of the overlasted upper from the lip or rib outward.

A further feature of the invention relates to the production of a definite, accurate, boundary line or edge about the tooled area of the overlasted upper. As shown, this may be accomplished by the provision of means, preferably acting yieldingly, for pressing the lasted upper of the shoe closely against the side of the last adjacent to the corner defined by the intersection of the side and bottom faces of the last, thus forming a definite angle in the upper at the intersection of the side and overlasted portions thereof and making it easy to confine the action of the tool to exactly the overlasted portion of the upper, which is the portion that it is desired to prepare.

Inasmuch as the portion of the upper which

is to be tooled comprises a band of overlasted upper material of a width which does not vary greatly and has the same contour as the insole lip or rib, the said lip may be utilized with advantage in presenting the work progressively to the tool, and, in one of its aspects, the invention includes that improvement in methods of making shoes having lipped or ribbed insoles which comprises tooling the surface of a portion of an upper lasted over the margin of the insole while utilizing the insole lip to facilitate the tooling operation. The lip may be utilized to secure relative progressive movement between the work and tool, or as a guide for such movement, or both.

These and other features and advantages of the invention will be more fully understood and appreciated from reading the following detailed description of a machine embodying the invention and a manner of practicing the method, in connection with the accompanying drawings in which

Fig. 1 is a side elevation of the operating mechanism of the machine, with parts broken out to reveal the internal structure;

Fig. 2 is a plan view, taken upon the line II-II of Fig. 1, showing the action of the work feeding mechanism;

Figs. 3 and 4 are fragmentary views showing the roughening tool, the feed fingers and the upper presser in operative relation to the work in the forepart and shank portions of a shoe, respectively; and

Fig. 5 is a perspective view of a shoe which has been operated upon.

Referring now to Fig. 1, 10 indicates a suitable base or column upon which is secured a housing 12 supporting the operating mechanism. Journaled in the housing 12 is a shaft 14 which is continuously driven, as by an electric motor or any other suitable source of power.

Gear teeth 16, formed upon the shaft 14, 45 constitute a pinion which meshes with a spur gear 18 secured to a shaft 20 also journaled in the housing 12 and connected by a positive clutch 22 to a shaft 24 to the outer end of which is secured a miter gear 26 meshing with 50 a similar miter gear 28 secured to a vertical eccentric shaft 30, the purpose of which will be described in detail hereinafter.

A bevel gear 32, fast upon the outer end of the shaft 14, meshes with and drives a bevel gear 34 which is secured to the upper end of an inclined rotating shaft 36. Removably secured to the lower end of the inclined shaft 36, by means of a screw 38 (see Fig. 3) 55 is an upper treating or roughening tool 40 which, as illustrated, is of the greater type, but may be of any kind suitable for tooling the shoe upper in a manner to produce the desired surface thereon. The illustrated tool is designed to remove the surface finish from 60 the upper leather and to roughen the leather 65

slightly to prepare it for the application of cement.

Loosely mounted at the back of the tool 40 is a frusto-conical disk-like work guiding member or gage 42 which is free to rotate 70 about the axis of the shaft 36 but is restrained from bodily movement in all directions.

While the tool 40 is power driven and rotates continuously, the guide member 42 is adapted to enter and engage in the angle 75 formed by the portion 44 of the upper of a shoe 46 on a last 48 and the upstanding portion 50 of said upper. 52 indicates the insole 80 of the shoe and 54 designates the insole lip or rib to which the upstanding portion 50 of the upper is lasted and secured and against which it rests. The portion 44 of the upper, which is drawn over the marginal portion 56 of the insole, is, for the purpose of identification, designated in the present specification 85 and the appended claims as the overlasted upper or the overlasted portion of the upper.

It will be seen that the progressive presentation of the surface of the overlasted upper to the tool 40 is facilitated by the guiding action of the disk-like member 42 running in the angle formed by the upper at the outside of the insole lip or rib and co-operating with the lip or rib. For the purpose of further facilitating this progressive presentation 90 of the work to the tool there are provided feed fingers 58, 60 having pointed ends adapted to penetrate the inner side of the insole lip or rib 54 and feed the shoe progressively 95 relatively to the tool 40, in the direction of the lip.

The feed fingers 58, 60 are carried respectively by oscillatory slides 62, 64 guided in a casing 66 supported by a bushing 68 surrounding the shaft 24 and by a rod 70 which is slidable horizontally in a stationary bracket 72, to which rod the casing 56 is secured by set screws 74. The bushing 68 is parallel to the rod 70 and is mounted to slide in a stationary bracket 76 formed upon the housing 12, the casing 66 being secured to the said bushing by a set screw 78 and the clutch 22 being constructed to permit endwise movement of the shaft 24 relatively to the shaft 20 while maintaining the two shafts in operative, driving engagement.

A very strong spring 80, one end of which is secured to the bracket 72 and the other end of which is secured to the rod 70, tends to move the rod and consequently the work feeding mechanism toward the left, as viewed in Fig. 1, causing the points of the feed fingers 58, 60 to engage the insole lip. For the purpose of retracting the feed fingers to permit the insertion of the insole lip and the upstanding portion 50 of the upper between the feed fingers and the guide disk 42, there is provided a bell crank lever, one arm 82 of which engages a collar 84 secured to the rod 70 and the other arm 85 of which is connected 130

by a link 86 to a rock shaft 88 constructed to be actuated by a treadle rod 90, the arrangement being such that when the treadle is depressed the feed mechanism is retracted to 5 provide space for the insertion of the work.

The rear ends of the slide 62, 64 are slotted, as seen at 92 (Fig. 2) and embrace a pin 94 which is secured in the casing 66 by a set screw 96. The intermediate portions of the 10 slides are engaged respectively by eccentric 98, 100 upon the vertical, rotating shaft 30 which eccentric impart to the slides a combined reciprocating and oscillating movement the effect of which is to cause the points 15 of the feed fingers 58, 60 to move in approximately elliptical paths, as shown by the broken line 102. These paths are substantially identical but the eccentric 98, 100 are offset angularly relatively to each other so that 20 the feed fingers engage the work alternately and feed it substantially continuously.

An overhanging bracket 104 mounted upon the bearings for the shaft 36 affords a support for a guide 106 in which is mounted a 25 slide 108 carrying a presser 110 adapted to engage and press the lasted upper of the shoe closely against the side of the last adjacent to the corner defined by the intersection of the side and bottom faces of the last, as illustrated 30 in Figs. 3 and 4. The purpose of this is to form the shoe upper to a definite angle or corner at the intersection of the side and overlasted portion thereof, thus making it easy to confine the action of the tool 40 to exactly 35 the overlasted portion 44 of the upper, which is the only part upon which it is desired that the tool shall act. The slide 108 is connected to a bell crank lever 112 acted upon by a stiff spring 114 which, however, is weaker than 40 the spring 80 so that the work will be positioned against the work guiding member 42. The spring 114 urges the presser 110 yielding toward the tool 40 and presses the lasted upper closely against the side of the last.

45 In operation the treadle is depressed, retracting the feed fingers 58, 60 and permitting the lasted shoe to be presented to the machine with the insole lip, and the upstanding marginal portion of the upper 50 which is lasted thereto, positioned in the space between the feed fingers and the work guiding member 42. In thus presenting the shoe to the machine the side portion of the upper, adjacent to the shoe bottom, is pressed 55 firmly against the presser 110, the yielding mounting of which permits the work to be positioned against the guide 42, while maintaining considerable pressure upon the upper and drawing it tightly over the edge of 60 the insole, forming a well defined corner or edge to determine the exact boundary of the area upon which the roughening tool 40 can operate.

The treadle now being released, the feed 65 fingers are advanced by the spring 80 until

their points enter into work feeding engagement with the inner side of the insole lip or rib. With the work thus positioned, the rotating tool 40 engages and operates upon the definitely determined surface area of the 70 overlasted portion 44 of the upper, the feed fingers 58, 60 utilizing the insole lip to feed the work progressively in the direction in which said lip extends and the work guiding member 42 also utilizing the lip, through the 75 upstanding portion of the upper which is lasted thereto, as a guide to determine accurately the direction of the feeding movement.

Since the guide member 42 is bodily immovable and resists the thrust of the feed 80 fingers normally to the insole lip, both the progression of the work past the tool 40 and the determination of the path in which it moves are effected mechanically at a substantially uniform rate, thereby facilitating 85 the even uniform action of the tool 40 upon the overlasted upper of the shoe.

The feed mechanism acts rapidly to advance the work past the treating tool from one end to the other of the area to be toolled, 90 whereupon the treadle is again depressed permitting the work to be removed from the machine. The tooled surface of the overlasted portion of the upper appears as shown 95 at 44 in Fig. 5 and is in the best possible condition for the reception of sole attaching.

Having described the invention, what is claimed as new and desired to be secured by Letters Patent is:

1. In a machine for tooling the overlasted portion of the upper of a lasted shoe, a tool adapted to operate upon the surface of the overlasted portion of the upper, combined with means for causing progressive movement of the shoe past the tool while the tool 100 operates upon said overlasted portion.

2. In a machine for tooling the overlasted portion of the upper of a lasted shoe, a tool adapted to operate upon the surface of the overlasted portion of the upper, combined with means for feeding the shoe past the tool 105 at a substantially uniform rate while the tool operates upon said overlasted portion.

3. In a machine for tooling the surface of the overlasted portion of the upper of a lasted shoe, the combination of a tool adapted to operate upon the overlasted portion of the upper, and means constructed and arranged to engage the insole of the shoe and feed the 110 shoe past the tool.

4. In a machine for roughening the surface of the overlasted portion of the upper of a lasted shoe having a lipped or ribbed insole, the combination of a tool adapted to roughen the overlasted portion of the upper 115 to prepare it for cement, and work feeding means constructed and arranged to engage the insole lip or rib and feed the shoe past the tool.

5. In a machine for tooling the upper of 120

- a lasted shoe, the combination of a tool for treating a portion of the upper and mechanism comprising an oscillating feed finger movable into and out of engagement with the work for causing progressive movement of the shoe past the tool.
6. In a machine for tooling the upper of a lasted shoe, the combination of a tool for treating a portion of the upper, and mechanism comprising a plurality of oscillating feed fingers constructed and arranged to engage alternately a portion of the shoe and feed it continuously past the tool.
7. In a machine for roughening the overlasted portion of the upper of a lasted shoe having a lipped or ribbed insole, the combination of a roughening tool adapted to operate upon the overlasted portion of the upper, and work guiding means constructed and arranged to co-operate with the insole lip or rib to guide the shoe relatively to the tool.
8. In a machine for tooling the overlasted portion of the upper of a lasted shoe having a lipped or ribbed insole, the combination of a tool adapted to operate upon the surface of the overlasted portion of the upper outside of the insole lip or rib, work guiding means constructed and arranged to engage the upstanding portion of the upper at the outside of the lip or rib, and work feeding means constructed and arranged to engage the inner side of the lip or rib.
9. In a machine for operating upon the bottom of a lasted shoe having a lipped or ribbed insole, the combination of an operating tool, feed mechanism operating upon one side of the insole lip or rib, and a frusto conical member adapted to enter the angle formed by the other side of the lip or rib and the bottom of the insole, said frusto conical member constituting both a work guide and an abutment for resisting the pressure of the feed mechanism.
10. In a machine for operating upon the bottom of a lasted shoe having a lipped or ribbed insole, the combination of an operating tool, insole lip or rib penetrating feed fingers, and a frusto conical work guiding member co-operating with the insole lip or rib to resist the thrust of the feed fingers as they penetrate the lip or rib to secure operative engagement therewith.
11. In a machine for roughening the overlasted upper on the bottom of a lasted shoe having a lipped or ribbed insole, the combination of a frusto conical roughening tool and a work guide, both constructed and arranged to operate in the angle formed by the insole lip or rib and the shoe bottom.
12. In a machine for roughening the overlasted upper on the bottom of a lasted shoe having a lipped or ribbed insole, the combination of a frusto conical roughening tool and a frusto conical work guiding member arranged base to base and adapted to operate in the angle formed by the insole lip or rib and the shoe bottom.
13. In a machine for operating upon the overlasted portion of the upper of a lasted shoe having a lipped or ribbed insole, the combination of a tool adapted to operate upon the surface of the portion of the upper overlying and parallel to the bottom of the insole, and feed mechanism constructed and arranged to engage the insole lip or rib and cause the work to move relatively to the tool in the direction in which said lip or rib extends.
14. In a machine for operating upon the overlasted portion of the upper of a lasted shoe, the combination of means for pressing the upper against the side of the last in the shoe adjacent to the bottom of the shoe, to produce a well defined corner or angle in the upper, and a tool adapted to operate upon the surface of the upper at one side of and up to said corner or angle.
15. In a machine for tooling the overlasted upper of a lasted shoe, the combination of means for producing a well defined corner or angle in the upper, and a tool adapted to roughen the surface of the upper at one side of and up to said corner or angle.
16. In a machine for roughening the surface of the upper on the bottom of a lasted shoe, the combination of means for pressing the upper against the side of a last in the shoe closely adjacent to the bottom of the shoe, and means for roughening the surface of the upper upon the shoe bottom closely adjacent to said pressing means.
17. In a machine for tooling the overlasted portion of the upper of a shoe upon a last, the combination of a yieldingly mounted presser for pressing the lasted upper of the shoe closely against the side of the last adjacent to the corner defined by the intersection of the side and bottom faces of the last, a tool adapted to operate upon the surface of the overlasted portion of the upper, and work feeding means constructed and arranged to cause progressive movement of the shoe past the tool and the pressing means.
18. In a machine for operating upon the overlasted portion of the upper of a lasted shoe having a lipped or ribbed insole, the combination of a tool adapted to operate upon the overlasted portion of the upper, a presser member spring pressed inward against the side face of the upper, and work feeding means spring pressed outward into engagement with the inner side of the insole lip or rib, the spring tension on the work feeding means being greater than that on the presser member.
19. That improvement in methods of making shoes having lipped or ribbed insoles which comprises tooling the surface of a portion of an upper lasted over the margin of the

insole while utilizing the insole lip or rib to facilitate the tooling operation.

20. That improvement in methods of making shoes having lipped or ribbed insoles which comprises tooling the surface of a portion of an upper lasted over the margin of the insole and utilizing the insole lip or rib to secure relative progressive movement between the work and the tool.

10 21. That improvement in methods of making shoes having lipped or ribbed insoles which comprises tooling the surface of a portion of an upper lasted over the margin of the insole and utilizing the insole lip or rib as a guide for determining relative movement between the work and the tool.

20 22. That improvement in methods of making shoes having lipped or ribbed insoles which comprises tooling the surface of a portion of an upper lasted over the margin of the insole and utilizing the insole lip or rib to secure relative progressive movement between the work and the tool and as a guide to determine the direction of said movement.

25 23. That improvement in methods of operating upon a lasted shoe having a lipped or ribbed insole which comprises roughening the surface of a portion of an upper lasted over the margin of the insole and utilizing the insole lip or rib to secure progressive movement of the work relative to the roughening tool.

In testimony whereof I have signed my name to this specification.

35 HENRY F. GOYETTE.
